CLAIM

The ornamental design for a lamp, as shown and described.

DESCRIPTION

FIG. 1 is a top, back, left side perspective view of a lamp, showing my new design;

FIG. 2 is a bottom, front, right side perspective view thereof;

FIG. 3 is a front elevational view thereof;

FIG. 4 is a back elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded view of the lamp in FIG. 1, with the base detached.

The broken lines shown in the drawings depict portions of the lamp that form no part of the claimed design.
